UNITED STATES PATENT OFFICE.

FRANK A. SULLIVAN AND WILLIAM L. LUKENS, OF BETHLEHEM, PENNSYLVANIA,
ASSIGNORS TO BETHLEHEM STEEL COMPANY, OF SOUTH BETHLEHEM, PENNSYLVANIA, A CORPORATION OF PENNSYLVANIA.

FUSE.

1,342,652.

Specification of Letters Patent.

Patented June 8, 1920.

Application filed January 11, 1917. Serial No. 141,876.

To all whom it may concern:

Be it known that we, FRANK A. SULLIVAN and WILLIAM L. LUKENS, citizens of the United States, and residents of Bethlehem, 5 Lehigh county, State of Pennsylvania, have invented certain new and useful Improvements in Fuses, of which the following is a specification.

This invention relates to a sensitive point 10 fuse and has for its principal objects to provide a fuse which will be caused to explode by striking objects offering practically no resistance to penetration, such as balloons and airships, and to provide means 15 for locking the parts in safe position which are only released by firing the projectile, whereby the latter may be handled with the maximum degree of safety. Other objects 20 will appear from the description, taken in connection with the drawings, in which—

Figure 1 is a longitudinal sectional view of the fuse showing the location of the same in the projectile, the outline of the latter being indicated by dotted lines;

Fig. 2 is a sectional view taken substantially on the line 2—2 of Fig. 1 and showing the centrifugal shutter which carries the primer;

Fig. 3 is a section substantially on the line 0 3—3 of Fig. 2 and showing the primer and related parts in section;

Fig. 4 is a longitudinal sectional view of the fuse showing the parts in the positions which they occupy when the needle holder 5 has been pushed inwardly by contact with any object.

The fuse comprises a body 11 having a rearwardly extending threaded shank or collar portion 12 which may be screwed into the body 10 of the projectile, which is indicated in dotted lines in Fig. 1. Where this fuse body joins the body of the projectile the outside surfaces are arranged so that they are flush and the contour of the projectile thereby maintained smooth. At its forward end the fuse body is formed with a circular recess 13 in which is slidably mounted the sleeve or shank 14 of the needle holder 15. A plurality of recesses 16 are formed to intersect the recess 13 and extend transversely or substantially perpendicular to the axis of the fuse. A boss 17 extends into the recess 13 and has slidably mounted therein the needle 18 which may be con-

nected to the needle holder in any desired 55 manner, and is shown as having the screw-threaded end 19, which is screwed into the holder 15. The needle 18 has the pointed end 20 opposite the threaded end 19 and is formed with a slot 21 through which extends the needle stop pin 22, which has its ends secured within the boss 17. As will appear from the drawing, an annular space is 60 formed between the sleeve 14 of the needle holder and the boss 17 and a spring 23 is 65 located in this annular space with one end thereof in contact with the fuse body and the other end bearing against the needle holder. Thus it will be apparent that the spring 23 tends to project the needle holder 70 in front of the fuse and that the stop pin 22 operating in the slot 21 of the needle limits the extent of this projection. A centrifugal bolt 24 is mounted in each of the recesses 16 and is forced inwardly toward the axis of 75 the fuse by a spring 25, the outer end of which acts against a screw plug 26. The sleeve 14 of the needle holder is formed of such a length that when it is in projected position the bolts 24 will be held in the path 80 of inward movement of the inner end of the said sleeve. In other words, the bolts 24 act as locking or safety means to prevent inward movement of the needle holder and the needle, if the holder is struck or any 85 force acts on the same to push it inward. It will be noted that the outer end of the needle holder is rounded and that a water-proof case 27 passes around the same and has its end crimped into a recess 28 formed in the 90 fuse body just back of the recesses 16. Thus the parts in the head of the fuse are protected.

The sleeve or shank 12 of the fuse body is also threaded interiorly and has mounted 95 therein the cylindrical stock or casing 29. It will be observed that the end of the stock or casing which fits in the sleeve 12 is enlarged and that the bore 30 of the said sleeve 12 is formed with a shoulder 31, whereby 100 the end of the stock or casing is spaced from the bottom 32 of the recess in the fuse body. A brass obturator 33 is interposed between the end of the stock or casing and the shoulder 31, thereby being held securely in 105 position. In the space between this disk 33 and the bottom 32 of the recess a centrifugal shutter 34 is mounted on a pivot 35, eccen-

trically located with respect to the axis of the projectile and this shutter carries a primer 36, which is normally held out of the axis of the fuse and the path of movement of the needle 18 by a spring 37, as illustrated in Fig. 2. It will be apparent that when the projectile is fired that the rotation of the latter will develop centrifugal force in the shutter 34 and on account of its eccentric mounting in the fuse the primer 36 will be moved to the axis of the fuse and in the path of movement of the needle 18. As shown in Fig. 3 the fuse body is formed with an expansion chamber 38 in front of the primer when the latter is in its normal or eccentric position. Thus if the primer is prematurely ignited the gases will expand into the chamber 38 and no damage will be done.

20 The stock or casing is hollow and at the enlarged end is formed with a recess 39, the end of which is adapted to be closed by a screw plug 40 having a central bore 41. A centrifugal cage 42 is located in this recess 39 and is of substantially frusto-conical shape. It has its base flanged out as at 43 and secured between the screw plug 40 and the bottom of the opening into which the screw plug seats. This centrifugal cage 30 comprises a series of substantially longitudinally extending fingers 44 having the weighted ends 45 which are adapted to catch behind and hold the end of a plunger 46 against longitudinal movement. When the 35 projectile is fired the rotation of the same will develop sufficient centrifugal force in the fingers 44 so that they will spread apart and permit the plunger to move toward the front of the projectile. As clearly shown in Fig. 1, the stock or casing is formed with an inwardly extending flange 47 spaced rearwardly a slight distance from the enlarged recess 39. A soft lead shock absorbing pad 48 is seated against the forward side of this 40 flange and between this pad and the flanged end 49 of the plunger 46 an expansion spring 50 is interposed, thus tending to force the plunger forward. This plunger is formed with a flame conduit 51 and at its forward 45 end carries the black powder delay pellet 52. At its other or rearward end it carries a fulminate detonator charge 53 which may be mounted in a copper tube and the ends thereof cushioned by means of the felt washers 54. This detonator charge is held in position by the screw plug 64 inserted in the end of the plunger. This end of the plunger is arranged in an auxiliary casing or liner 55, which at its forward end has the inwardly 50 extending flange 56 formed with a bore for the plunger 46, and at its rearward end is threaded and screwed into the end of the stock or casing and locked in position by a screw plug 57 which closes the end of the 60 said casing. The end of the plunger carry-

ing the detonator is mounted in a support 58 which prevents the end of the same from whipping when fired. Thus it will be apparent that the detonator charge is arranged in the fuse in a chamber separate from the other parts, whereby if it is accidentally ignited the force of the explosion will be dissipated in the expansion chamber of the fuse without causing any damage.

Between the flange 56 and the flange 47 of the stock or casing is arranged an annular booster charge 59, and between its forward end and the flange 47 is arranged the asbestos washer 60, and between its rearward end and the flange 56 a like asbestos washer 61 and a cover disk 63 are located. Between the disk 63 and the flange 56 in an annular space bounded at the inner edge by the plunger 46 is located an eccentric ring 62, which is formed with a circular opening 85 through which extends the plunger 46. The mounting of this ring is such that when the projectile is fired the rotation thereof develops centrifugal force which tends to move it transversely with respect to the axis 90 of the projectile, whereby when the plunger has moved to its forward position as illustrated in Fig. 4 this eccentric ring will move across the path of the plunger, thereby preventing its return to its original position.

Fig. 1 shows the parts in their normal and safe positions. When the projectile is fired, however, and after it has ceased to be accelerated, the rotation of the same causes the centrifugal bolts 24 to move outward, thereby freeing the end of the needle holder so that when the latter strikes any object it will be pushed inward, carrying with it the needle or firing pin 18. At about the same time that the centrifugal bolts 24 are moved outward, the centrifugal shutter 34 will move so as to bring the primer 36 into the path of the needle or firing pin 18. The fingers 44 of the centrifugal cage will also be expanded by the centrifugal force, thus removing them from the path of movement of the end of the plunger 46 and permitting the spring 50 to force the plunger forwardly into the position shown in Fig. 4. This, of course, will carry the fulminate detonator charge 53 so that it will occupy a position within the booster charge 59, as shown in Fig. 4. Thus when the needle holder strikes an object the needle or firing pin 18 will penetrate the primer 36 and the ignition of the same will cause sufficient pressure to puncture the obturator disk 33 and ignite the delay pellet 52. The flame from this pellet will be conveyed along the flame conduit 51, thereby igniting the detonator charge 53 which in turn fires the booster charge 59, the latter being the only charge of sufficient strength to burst the stock or casing 29 and ignite the main charge of the projectile. Of course, the sensitiveness of the fuse may be 130

regulated by the tension of the spring 23, the weaker the spring the more sensitive the fuse. It will thus be observed that a fuse is provided which may be handled with a maximum degree of safety. The needle holder is locked against inward movement; the primer is normally held out of the path of movement of the needle; the delay pellet is spaced from the primer and has the interposed obturator disk to separate the two; and the detonator charge is located in an independent and sufficiently large chamber and out of register or operative position with the booster charge.

15 Although the primer 36 is described and illustrated in connection with a detonating fuse, it is obvious that this primer together with the needle and associated parts are not limited to such a fuse, as they might be used for firing powder charges of any kind or charges of a different nature, such as incendiary charges.

Having thus described the invention what is claimed and desired to be secured by Letters Patent is:

1. A sensitive impact fuse for a projectile comprising a primer, a fuse body adapted to be secured to the front of the projectile and formed with a cylindrical recess open 30 at the front thereof, a part projecting at the front of the projectile having a sleeve slidably fitted in said recess, said part adapted to be actuated by the impact of the projectile to cause ignition of the primer, a 35 spring within said sleeve acting to project said part, and a bolt adapted to be released by firing the projectile engaging the rear end of the sleeve for locking said part in said projected position.

40 2. A sensitive impact fuse for a projectile comprising a primer, a movably mounted part projecting at the front of the projectile adapted to be actuated by the impact of the projectile to cause ignition of the primer, yielding means acting to project said part, means adapted to be released by firing the projectile for normally locking said part in projected position, a charge normally in a safe position, yielding means acting to move 45 said charge to operative position and means adapted to be released by firing the projectile for holding said charge in said safe position.

3. A sensitive impact fuse for a projectile 55 comprising a primer, a needle, a movable part projecting at the front of the projectile carrying said needle and adapted to be actuated by the impact of the projectile to cause ignition of the primer, a sleeve on said part surrounding said needle, a spring arranged within said sleeve acting to project said part, and a bolt engaging the rear end of the sleeve adapted to be released by firing 60 the projectile, said bolt normally locking said part in projected position.

4. A sensitive impact fuse for a projectile comprising a primer, a fuse body adapted to be secured to the front of the projectile, a part slidably fitted in said body and projecting at the front thereof adapted to be 70 actuated by the impact of the projectile to cause ignition of the primer, said part having its projecting front end rounded, yielding means acting to project said part, and a thin sheet metal water-proof casing carried 75 by the body inclosing said part and formed to constitute a smooth surface in continuation of that of the projectile, its front end being rounded to fit the rounded front end of said part.

15 5. A sensitive impact fuse for a projectile comprising a primer, a movably mounted part projecting at the front of the projectile adapted to be actuated by the impact of the projectile to cause ignition of the primer, 80 yielding means acting to project said part and means adapted to be released by firing the projectile for normally locking said part in projected position, said primer normally held out of the path of movement of said 85 part and mounted to be automatically moved into said path after the projectile has been fired.

6. A sensitive impact fuse for a projectile comprising a movably mounted part projecting at the front of the projectile, yielding means acting to project said part, a primer adapted to be ignited by said part when the latter is moved inward by impact, a charge normally in safe position adapted 90 to be ignited from the primer and means for automatically moving said charge to operative position after the projectile has been fired.

7. A sensitive impact fuse for a projectile 105 comprising a movably mounted part projecting at the front of the projectile, yielding means acting to project said part, a primer adapted to be ignited by said part when the latter is moved inward by impact, 110 a delay pellet normally spaced from the primer, means for automatically moving said pellet into a position whereby it may be ignited by the primer after the projectile has been fired, and a charge adapted to be 115 ignited by said pellet.

8. A sensitive impact fuse for a projectile comprising a movably mounted part projecting at the front of the projectile, yielding means acting to project said part, a 120 primer adapted to be ignited by said part when the latter is moved inward by impact, a hollow plunger having a delay pellet at one end spaced from the primer and a charge at the other end, and automatic 125 means for moving said plunger when the projectile is fired to carry the pellet into a position to be ignited by the primer.

9. A sensitive impact fuse for projectiles comprising a fuse body adapted to be at- 130

tached to the front of the projectile, a needle holder slidably mounted in said body and normally projecting at the front thereof, a spring acting to force said holder into projected position, stop means for limiting the amount which said holder projects, a needle carried by said holder, and a primer adapted to be ignited by said needle upon impact of the projectile, and a slidable bolt engag-

ing said holder to positively maintain it in 10 projected position, said bolt adapted to be automatically moved out of the path of the holder by firing the projectile.

In testimony whereof we affix our signatures.

FRANK A. SULLIVAN.
WILLIAM L. LUKENS.
